United States Patent Office

Des. 180,052
Patented Apr. 9, 1957

180,052

HAT

Philip E. Young, Arcadia, Calif., assignor to George S. Bailey Hat Company, Los Angeles, Calif., a corporation of California

Application September 29, 1955, Serial No. 38,158

Term of patent 14 years

(Cl. D3—13)

Fig. 1.

Fig. 2.

Fig. 3.

Fig. 1 is a front elevational view of a hat showing my new design;

Fig. 2 is a side elevational view of the hat shown in Fig. 1, looking from the right toward the left; and

Fig. 3 is a rear elevational view of the hat shown in Fig. 1.

I claim:

The ornamental design for a hat, as shown.
